AIR CONDITIONER FRONT PANEL

Paul E. Stratton, Jr., Rochester, Mich., assignor to Chrysler Corporation, Highland Park, Mich., a corporation of Delaware

Application December 18, 1957, Serial No. 48,944

Term of patent 14 years

(Cl. D62—4)

Fig. 1 is a front elevational view of an air conditioner front panel showing my new design;

Fig. 2 is a side elevational view thereof;

Figs. 3 and 4 are enlarged sectional views taken on the lines 3—3 and 4—4 respectively of Fig. 1; and

Fig. 5 is an enlarged fragmentary perspective view of a portion of the air conditioner front panel.

I claim:

The ornamental design for an air conditioner front panel, substantially as shown.
